CLAIM

The ornamental design for the reflective height measuring device, as shown and described.

DESCRIPTION

FIG. 1 is a top plan view of a reflective height measuring device showing our new design, the bottom plan being identical;

FIG. 2 is a front elevational view thereof, the rear being plain and unornamented;

FIG. 3 is a typical side elevational view thereof.
 The back view of the reflective height measuring device is plain.

FIG. 1

FIG. 3

FIG. 2
